US0D1099599S

(12) **United States Design Patent** (10) **Patent No.:** **US D1,099,599 S**
(45) **Date of Patent:** **** Oct. 28, 2025**

(54) **DISPLAY ASSEMBLY**

(71) Applicant: **ALL PLASTIC, INC.**, Rancho Cordova, CA (US)

(72) Inventors: **William Thomas Smith**, Fair Oaks, CA (US); **Cheryl Ann Smith**, Fair Oaks, CA (US)

(73) Assignee: **ALL PLASTIC, INC.**, Rancho Cordova, CA (US)

(**) Term: **15 Years**

(21) Appl. No.: **29/819,653**

(22) Filed: **Dec. 16, 2021**

(51) LOC (15) Cl. **06-04**

(52) U.S. Cl. **D6/682**
USPC ....

Primary Examiner — Steven J Czyz

CLAIM

The ornamental design for a display assembly, as shown and described.

DESCRIPTION

FIG. 1 is a perspective view of a display assembly in accordance with said design;

FIG. 2 is a left side view of the display assembly shown in FIG. 1;

FIG. 3 is a front view of the display assembly shown in FIG. 1;

FIG. 4 is a rear view of the display assembly shown in FIG. 1;

FIG. 5 is a right side view of the display assembly shown in FIG. 1;

FIG. 6 is a top plan view of the display assembly shown in FIG. 1;

FIG. 7 is a bottom plan view of the display assembly shown in FIG. 1; and,

FIG. 8 is a perspective view of the display assembly, shown in use with environment.

All surfaces not shown form no part of the claimed design. The shade lines in the Figures show contour and not surface ornamentation. The oblique line shading in the Figures shows a transparent surface and not surface ornamentation. The broken lines depict portions of the article and environment that form no part of the claimed design.

1 Claim, 8 Drawing Sheets
